ABSTRACT OF THE DISCLOSURE

Latching means for a needle up or narrowing picker of a circular knitting machine which is operative to latch the picker in raised up picking position following its up picking operation during reciprocatory operation of the machine in one direction and which is operated to release the picker for movement to lowered position for the next up picking operation during reciprocatory operation of the machine in the opposite direction.

BACKGROUND OF THE INVENTION

Conventionally circular knitting machines having a needle cylinder adapted for both rotary and reciprocatory operation to form fabric tubes such as stockings with reciprocatorily knitted heel and toe pockets, are provided with forward and reverse stitch drawing cams, a pivoted needle up picker associated with each stitch cam for raising needles from a knitting path to a non-knitting path and a down picker for lowering needles from the non-knitting path to the knitting path to fashion the pockets. Each up picker is normally nested in a depression in the upper surface of its associated stitch cam in position to be engaged and operated by the butt of a leading needle, at one or the other end of the pocket forming group of needles, to raise the needle from the knitting path to the non-knitting path. After releasing the butt of the leading needle in the non-knitting path the up picker is immediately moved toward its nested position in the depression in the stitch cam by a spring at which time it engages and drives the butts of a few of the remaining needles of the pocket forming group downwardly into the depression to deflect these needles from the knitting path. The needles so deflected are then raised as the butts thereof again ride out of the depression in the stitch cam. Normally this upward movement of the needles as the butts ride out of depression in the stitch cam, which is at relatively high speed, is arrested by a center cam associated with the stitch cams at the approximate level of the knitting path. However, it sometimes occurs that a more freely operating needle is raised before reaching the center cam to a level above the knitting path in which the butt thereof will strike and be damaged by the end of the center cam.

Heretofore it was proposed to prevent this engagement between the up pickers and needle butts and the resulting defective operation of the needles caused thereby by providing mechanism, such as shown in U.S. Pat. No. 540,151 issued May 28, 1895, for latching the up pickers in raised positions following each needle up picking operation thereof. In the machine of this patent the needle cylinder was stationary and the pickers were reciprocated with the stitch cams during needle picking operations. Each up picker was moved in a guide by a needle from lowered to raised up picking position in one direction of reciprocation of the picker against the action of a compression spring and a first pivoted lever was moved beneath the picker by spring means to latch the picker in raised up picking position. A second pivoted lever was operated by a fixed stop member during reciprocation of the picker

2

in the direction opposite to its picking movement to move the first lever from latching position to permit the picker to return to its lowered position.

In another proposed form of mechanism for retaining the up pickers in raised position after each up picking operation, such as disclosed in U.S. Pat. No. 2,861,440, issued Nov. 25, 1958, the up pickers, which are of a conventional pivoted type, are connected by a link so that movement of one picker from lowered to raised up picking position during a reciprocation of the needles in one direction moves the other picker from raised to lowered position for its up picking operation during reciprocation of the needles in the opposite direction.

SUMMARY OF THE INVENTION

Briefly summarized the invention resides in the provision of means for latching each of the up or narrowing pickers of a circular knitting machine in raised up picking position following a needle up picking operation thereof in one direction of reciprocatory operation of the needles and means which is movable with the needles during a reciprocation thereof in the opposite direction for operating the latching means to release the up picker for movement to a lowered position for its next up picking operation.

BRIEF DESCRIPTION OF THE DRAWINGS

FIG. 1 is a top plan view of a portion of a circular knitting machine incorporating mechanism according to the invention for controlling needle up picker devices of the machine;

FIG. 2 is a view on an enlarged scale of a portion of the mechanism of FIG. 1 with parts removed;

FIG. 3 is a view similar to FIG. 2 with parts removed and other parts shown in different operating positions;

FIG. 4 is a view on an enlarged scale looking in the direction of the arrow 4 of FIG. 1;

FIG. 5 is a cross-sectional view on an enlarged scale taken on the line and looking in the direction of the arrows 5—5 of FIG. 2;

FIG. 6 is a cross-sectional view on an enlarged scale taken on the line and looking in the direction of the arrows 6—6 of FIG. 2; and

FIG. 7 is a view on an enlarged scale of a portion of the mechanism of FIG. 1 with parts broken away for clearness of illustration.

Referring to FIG. 1 of the drawings there is shown a portion of a conventional circular knitting machine adapted for both rotary and reciprocatory operation to form tubular fabrics such as stockings the machine including a usual circle of needles indicated at 10 which are slidably mounted in slots in a cylinder 11, sinkers 12 slidably mounted in slots in a bed (not shown) and a sinker cap 15 having cams (not shown) for operating the sinkers in cooperation with the needles in forming yarns fed to the needles into courses of stitches of the stocking fabrics. The sinker cap 15, which is frictionally movable with the needle cylinder 11 during both rotary and reciprocatory operation, adjustably carries a bumper screw 16 for engagement with a bumper post 17 to limit the movement of the sinker cap with the cylinder to position the sinker cams in relationship to the operating path of the needles during rotary and forward reciprocatory strokes of the cylinder in a counterclockwise direction, as viewed in FIG. 1. A second bumper screw 20 adjustably carried in the sinker cap is adapted to engage the post 17 to limit the movement of the sinker cap with the cylinder to position the sinker cams in relationship to the operating path of the needles during reverse reciprocatory strokes of the cylinder in a clockwise direction.

The machine is provided with a main knitting station indicated generally at 21 having a forward stitch cam 22

for operating the needles 10 to draw stitches during rotary and forward reciprocatory strokes of the cylinder and a reverse stitch cam 25 for operating the needles in reverse reciprocatory strokes of the cylinder. Associated with the stitch cams 22 and 25 are up or narrowing picker units 26 and 27, respectively, for raising needles of group of needles, forming heel and toe pockets of the stockings, from a knitting path to a non-knitting path during reciprocatory operation of the machine. The machine is also provided with a conventional down picker unit (not shown) for lowering needles from the non-knitting path to the knitting path during formation of the heel and toe pockets of the stockings.

As shown in FIGS. 2 to 6, the picker unit 26 associated with the stitch cam 22 includes a bracket 30 which is secured by screws 31 to a cover plate 32 forming a part of the machine frame (FIG. 1), and a swivel member 35 which is provided with aligned lower and upper gudgeons 36 and 37 mounted in the bracket and a plate 40, respectively, secured by screws or studs 41 to the bracket, in a manner to permit the swivel member to pivot about an axis parallel to the axis of the cylinder 11. A picker member 42, positioned in an aperture 45 in the swivel member 35 and pivotally mounted on a pin or stud 46 carried in the swivel member at right angles to the axis of the gudgeons 36 and 37 (FIG. 5), has one arm 47 adapted to be engaged by the butts of the needles, as hereinafter set forth. The picker member 42 has a second arm 50 for following engagement with a cam plate 51 secured to the bracket 30 by screws 52 (FIG. 3). A spring 55 connected to the arm 47 of the picker member 42 and an ear 56 of the bracket 30 normally biases the picker member to its position of FIG. 2 at which time the arm 50 is in a notch or low part 57 of the cam plate 51 and the free end of the arm 47 is nested in a depression in the upper surface of the stitch cam 22 at a level to be engaged by the leading needle of the heel and toe forming groups of needles during reverse reciprocatory strokes thereof. The picker unit 27 associated with the stitch cam 25 is identical to the picker unit 26, except that certain of the parts are reversed in both structure and operation to permit the picker member of unit 27 to be engaged and operated by the leading needle of the heel and toe needle groups during forward reciprocatory strokes thereof, and like parts of both units will be hereinafter referred to by like reference characters.

During a reciprocatory stroke of the needles in the reverse or clockwise direction the leading needle of the group of needles following the knitting path engages the arm 47 and rotates the picker member 42 and swivel member 35 of the unit 26 counterclockwise about the axis of the gudgeons 36 and 37 from the position of FIGS. 1 and 2 to the position of FIG. 3. During this movement of the picker and swivel members about the axis of the gudgeons the arm 50 is moved from the notch 57 of the cam plate 51 to a high surface 60 thereof to also pivot the arm 47 of the picker member upwardly about the axis of the stud 46 to raise the leading needle to the non-knitting path. After the picker member and swivel member are rotated about the axis of the gudgeons sufficiently to disengage the arm 47 from the butt of the needle raised to the non-knitting path conventionally the spring 55 immediately acts to move the picker and swivel members towards the position of FIG. 2. At this time the arm 47 engages and drives the butts of a few of the remaining needles of the heel (or toe) group of needles into the depression in the stitch cam to deflect these needles from the knitting path and needles so deflected are again raised as the butts thereof ride out the depression in the stitch cam. The butts of a few of the heel (or toe) group of needles are moved into and out of the depression in the stitch cam 25 in a like manner following each up picking operation of the picker unit 27 in the forward or counterclockwise direction. During this movement of the butts of the needles into and out of the depressions in

the stitch cams it sometimes occurs that these needles are thrown above the knitting path to a position in which the butts thereof strike the end of the usual center cam (not shown) associated with the stitch cams which either bends or breaks the butts.

In order to prevent engagement of the up picker members of the picker units 26 and 27 with the butts of the needles remaining in the knitting path means is provided, in accordance with the instant invention, for latching each up picker member in its raised up picking position following an up picking operation thereof in one direction of reciprocatory movement of the needles and for releasing the picked member for movement to lowered position for the next up picking operation during a reciprocatory operation of the needles in the opposite direction. The means for latching the picker member of the unit 26 in its up picking position includes a lever 61 pivotally mounted on one of the studs 41 (FIGS. 1 and 2). A downwardly extending finger 62, secured by screws 65 to an outer free end of one arm 66 of the lever 61, is adapted to engage the swivel member 35 in the manner hereinafter set forth. The lever 61 has a second arm 67 for engagement with a downwardly projecting gear 70 of a member 71 secured to the sinker cap 15 by screws 72. A spring 75 connected between the arm 66 and one of the screws 41 tends to bias the lever 61 clockwise, as viewed in FIG. 2.

The picker member 42 of the unit 27 is adapted to be latched in its up picking position by a lever 76 pivotally mounted on one of the studs 41 (FIG. 1). The lever 76 has one arm 77 with a downwardly extending finger 81, secured to the free end thereof by screws 82, for engagement with the swivel member 35 of unit 27 and a second arm 83 for engagement with a downwardly projecting finger 84 of a member 85 secured by screws 86 to the sinker cap 15 (FIG. 1). A spring 87 connected between the arm 77 and one of the studs 41 tends to bias the lever 76 counterclockwise as viewed in FIG. 1.

Following a reciprocatory stroke of the heel (or toe) forming group of needles in the forward or counterclockwise direction and prior to the start of the reciprocatory stroke of these needles in the reverse or clockwise direction the picker member 42 of the unit 26 is in the position of FIG. 2 for a needle up picking operation. At this time the sinker cap 15 is in its position of FIG. 1 and the member 71 has moved the lever 61 counterclockwise to disengage the finger 62 from the swivel member 35 of the unit 26. Also at this time the picker member 42 of the unit 27 is latched in a raised up picking position, corresponding to the position of picker member 42 of unit 26 as shown in FIG. 3, by engagement of the finger 81 on the lever 76 with a surface 90 on the swivel member 35 of the unit 27 (FIG. 7). During the subsequent reverse stroke of reciprocation of the heel (or toe) forming group of needles the sinker cap 15 is rotated clockwise to the position determined by engagement of the bumper screw 20 with the bumper post 17 to move the member 71 out of engagement with the arm 67 of the lever 61 thereby permitting the spring 75 to turn the lever 61 to engage the finger 62 with a curved surface 91 of the swivel member of the unit 26. Also during this movement of the sinker cap 15 in the clockwise direction the member 85 engages and turns the lever 76 clockwise to move the finger 81 thereon out of engagement with the surface 90 on the swivel member 35 of the unit 27 thereby permitting movement of this swivel member and picker member thereon to a position corresponding to the position of the picker member of the unit 26 shown in FIG. 2 for the next up picking operation thereof. Thereafter when the picker member 42 of the unit 26 is moved to its raised position by the leading needle of the heel (or toe) group of needles the spring 75 turns the lever 61 clockwise to move the finger 62 into engagement with a surface 92 on the swivel member 35 of the unit 26 to latch it and the picker member in the up picking position, as shown in FIG. 3.

During the next reciprocatory stroke of the heel group of needles, which is in the forward or counterclockwise direction, the sinker cap 15 is rotated in the same direction to the position determined by engagement of the bumper screw 16 with the bumper post 17 to move the member 85 out of engagement with the lever 76 to permit the latter to move into latching engagement with the swivel member 35 of the unit 27 when the picker member 42 of this unit is moved to raised up picking position by the leading needle of the heel forming group of needles. Also during this movement of the sinker cap in the forward direction the member 71 is moved to engage and turn the lever 61 counterclockwise to disengage it from the swivel member 35 of the unit 26 thereby permitting this swivel member and the picker member 42 thereon to move to the position of FIG. 2 for the needle up picking operation in the next reverse reciprocatory operation of the needles.

It will be understood that the improvements specifically shown and described by which the above results are obtained can be changed and modified in various ways without departing from the invention herein disclosed and hereinafter claimed.

I claim:

1. In a circular knitting machine having a knitting station, a cylinder adapted for both rotary and reciprocatory operation, needles in said cylinder, cam means at said knitting station for operating said needles along a knitting path to form courses of stitches during rotary operation of said cylinder in a forward direction and for operating a group of said needles along knitting paths to form courses of stitches during reciprocatory operation of said cylinder in opposite directions, sinkers, a sinker cap having cam means for operating said sinkers in cooperation with said needles to form said courses of stitches, said sinker cap being movable with said needle cylinder in said opposite directions to move said sinker operating cam means to predetermined positions in relationship to said needle operating cam means, needle up pickers associated with said needle operating cam means, one of said up pickers being movable from lowered to raised positions to raise a leading needle at one end of said group from said knitting path to said non-knitting path during operation thereof in one of said opposite directions and another of said up pickers being movable from lowered to raised positions to raise a leading needle at the other one of said group from said knitting path to said non-knitting path during operation thereof in the other of said opposite directions, the improvement comprising means for latching

each of said up pickers in said raised position following movement thereof from said lowered to said raised position, and means rotatable with said cylinder in each of said directions of reciprocatory operation for operating the latching means, for the up picker moved to raised position during reciprocatory operation of said cylinder in the other of said directions, to release said last mentioned picker for movement from said raised to said lowered position.

2. A machine according to claim 1 in which said means rotatable with said cylinder for operating said latching means for each said pickers to release it for movement from said raised to said lowered position comprises said sinker cap.

3. A machine according to claim 1 in which said latching means for each of said pickers includes a pivoted lever, and means for moving said lever into latching engagement with said picker when in said raised position, and said means rotatable with said cylinder for operating said latching means to release said picker for movement from said raised to said lowered position includes said sinker cap and means on and movable with said sinker cap for moving said lever out of latching engagement with said picker.

4. A machine according to claim 1 in which each said picker is mounted on a swivel member and said swivel member is pivotally movable from a first position when said picker is in said lowered position to a second position when said picker is moved to said raised position, and said latching means for latching each of said pickers in said raised position includes a lever and means for moving said lever into latching engagement with said swivel member in said second position.

5. A machine according to claim 4 in which said means rotatable with said cylinder for operating said latching means includes said sinker cap and means on and movable with said sinker cap to move said lever from latching engagement with said swivel member to permit said swivel member to move to said first position.
